UNITED STATES PATENT OFFICE

CORTLANDT F. AMES, JR., OF MOUNT VERNON, NEW YORK, AND CHARLES W. MORTIMER, OF UPPER MONTCLAIR, NEW JERSEY, ASSIGNEES TO THE BARRETT COMPANY, A CORPORATION OF NEW JERSEY

SHINGLE

Application filed July 9, 1924. Serial No. 724,949.

This invention relates to shingles or shingle strips and the methods of cutting the same from sheets of roofing material, as well as the methods of installing the same on roofs. The 5 shingles or shingle strips are preferably cut from sheets of prepared roofing material which are usually made by saturating a so-called felt base with water-proofing material, such as asphalt or the like, coating the same 10 with plastic material such as asphalt for example, and then applying a layer of wear resisting material, such as crushed stone, crushed slate, or the like.

By the present invention shingles or shingle strips may be cut from sheets of roofing material with no waste, and attractive designs may be produced when the shingles or shingle strips are installed, and at the same 15 time provision is made for preventing the lower, or exposed ends from curling up, or being turned up by the wind.

The invention will be understood from the description in connection with the accompanying drawings, in which

20 Fig. 1 is a plan view of one form of the shingle.

Fig. 2 is a plan view of a modification.

Fig. 3 is an edge view of the same.

25 Fig. 4 is a plan view showing how shingles of Fig. 1 may be cut from a sheet of roofing material.

Fig. 5 shows how the same may be installed on a roof.

Fig. 6 is another modification.

30 Fig. 7 is a plan view showing how the shingles of Fig. 6 may be cut from a sheet of roofing material.

Fig. 8 is a plan view of a fourth modification.

35 Fig. 9 shows how the shingles of Fig. 8 may be cut from a sheet of roofing material.

Fig. 10 shows how the same may be installed on a roof.

In the drawings reference character 1 indicates the body of a shingle which is provided with a quadrilateral extension 2 along the middle portion of one edge thereof. This 45 extension 2 may however be made of rectangular shape if desired. The extension 2 has 50 attached to the under side, or under a lower

end thereof U-shaped hooks or clips 3 which are adapted to catch under the edge of shingles in a subjacent, or lower row of shingles, when the same are installed, as will be more clearly explained below. The clips or holding devices 3 may be attached to the extension 2 in any convenient manner, as for example by having tongues or projections 4 thereon which penetrate into the body of the shingle, and fasten the clip to the shingle. 55

It will be obvious from an inspection of Fig. 4 that the shingles may be cut from a strip of roofing material by slitting the same longitudinally along staggered lines 5, joining the ends of these lines by sloping lines 6 and severing the strips transversely along the lines 7 perpendicular to the lines 5, intersecting the same at their middle points. 60

If the strips are cut transversely along lines 7 that are perpendicular to the lines 5, but at the ends of these lines shingles of the shape indicated in Fig. 2 will be produced. It is obvious that sheets of roofing material that are two, or three, or more times the width of the one shown in Fig. 4 may be slit in a similar manner so as to produce four or six, etc. sets of shingles like the ones shown. Instead of severing the sheets transversely along the lines 7 to produce individual shingles the sheets may be severed transversely 70 at intervals two, or three or more times as far apart, thereby producing shingle strips with a plurality of individual shingles joined end to end without departing from the spirit or scope of this invention. The word shingle in this application is intended to include either an individual shingle, or a plurality of the same joined together as indicated. 75

The shingles produced, as above described, may be installed on a roof in horizontal rows 80 with their ends abutting. The super-posed rows are installed with their lower edges 9 even with the edges 10 of shingles in the preceding row, and with the lower sides of the hooks or fastening devices 3 extending under 85 the edges 10 of the lower shingles, and so on for successive rows.

The modification shown in Fig. 6 is similar to that shown in Fig. 2, except that the ends 100 12 and 13 are made sloping, the end 13 be-

ing in effect an extension of the sloping edge 14 of the projections 15. These shingles may be cut from a sheet of roofing material as shown in Fig. 7 without any waste, and are installed in a manner similar to that in connection with Fig. 5.

In the modification shown in Fig. 8 the shingles 16 are rectangular in shape, and have diagonal corners cut off as shown at 17 and 18, the clip or holder 19 being attached to the lower side of the corner 17. One of the other corners is provided as shown at 20 with a lip or triangular projection, one side of which 21 is parallel with a horizontal line through the shingle, the other corner may be provided with a similar lip 20' so that the shingle would be reversible, or this lip 20' may be cut off so as to leave a square corner. These shingles 16 may be cut from a strip of roofing material as shown in Fig. 9 along transverse lines 23 across the central portion of the strip and perpendicular to its edges a line 24 at an angle to the edge, and also along a line 25 parallel to the line 24, or along the lines 25 and line 26 that is an extension of line 23 depending upon whether the lip 20' (Fig. 8) is to be retained or not.

The shingles indicated in Fig. 8 may be installed as shown in Fig. 10 in horizontal rows 30 with the holders or clips 19 on the lower corners of shingles in super-posed rows catching under the lips 20 of shingles in subjacent rows as shown.

We claim:

1. A flexible shingle comprising an extending portion to be exposed to the weather, a body portion extending therefrom in the same plane and a U-shaped clip, said clip being entirely covered by said extending portion and having one arm thereof entirely secured to the underside of said extending portion so that the bend of said U is co-terminous with the lower edge of said extending portion and so that the other arm of the U-shaped clip may extend under the body portion of lower shingles when they are installed on a roof.

2. A flexible shingle having two portions terminating at different lines, and a U-shaped clip secured to the underside of and entirely covered by one portion and having the bend of the U substantially co-terminous with the edge of said portion, said clip being adapted to engage the other portion of a lower shingle when the shingles are installed on a roof whereby the lower edge of said portion abuts against the inner face of said bend.

3. In a shingle organization, the combination which comprises a flexible shingle having a portion to be exposed to the weather, a U-shaped clip secured to the underside of said portion, and a subjacent shingle having a portion to be exposed to the weather and another portion having a side thereof extending into said clip in abutting relationship

with the inner face of the bend of the U of said clip, said side of said subjacent shingle extending substantially parallel with said face of said bend, and said face being in undivided engagement with said side.

4. A flexible shingle comprising a body portion, an extension at one edge of said body portion, a U-shaped clip on the under surface of said extension, said clip when said shingles are laid upon a roof being positioned to have the body portion of the subjacent shingle between the arms of the U, the bend of the U engaging the forward edge of said body portion.

In testimony whereof we affix our signatures.

CORTLANDT F. AMES, JR.
CHARLES W. MORTIMER.
